UNITED STATES PATENT OFFICE.

JOHN A. ARTON, OF CHICAGO, ILLINOIS.

CONVERTIBLE FURNITURE.

1,281,265.

Specification of Letters Patent. Patented Oct. 15, 1918.

Application filed November 22, 1915. Serial No. 62,721.

To all whom it may concern:

Be it known that I, JOHN A. ARTON, a citizen of the United States, residing at the city of Chicago, in the county of Cook and State of Illinois, have invented certain new and useful Improvements in Convertible Furniture, of which the following is a specification.

My invention relates to convertible furniture, and particularly to that class thereof in which a davenport sofa is used as the foundation and which, by changes of the several parts, may be converted into a bed. My invention more particularly relates to that class of convertible sofas in which the change is made by a continuous or practically continuous movement of the parts. Theoretically the so-called one movement device is much to be desired, but all attempts heretofore to make such convertible furniture have resulted in complicated structures, of which the parts were likely to be disarranged and which were either heavy through the necessary use of counterweights or likely to become overbalanced with the possibility of injuring the operator.

In my invention hereinafter described, I am able to produce a simple, comparatively light, and easily operable device, which is so controlled and balanced as to be operated easily and without danger, in which the parts are extended by continuous movement under control of a special control device. My invention further provides means by which the bed fabric is tensioned from end to end as the bed members are extended, which tension is relieved as the bed is folded, thereby and by other features of construction making ample provision for bedding. Further details of construction, including a combined spring support and balancing device and a lock to be used in connection therewith, an improved pivoting device, and an improved foot rest and bedding holder will be more fully hereinafter described in the body of this specification and set forth in the claims.

The principles of my invention are illustrated in the drawings, in which—

50 Figure 1 is an end view of my improved sofa bed; one of the end pieces being removed to show the internal construction;

Fig. 2 is a similar view, the movable parts being partially extended;

55 Fig. 3 shows the same after the parts are fully extended;

Fig. 4 is a plan view of one side of Fig. 3; Fig. 5 is a plan of a portion of Fig. 2;

Figs. 6 and 7 are enlarged details partly in section of a foot board and bedding holder;

Fig. 8 is an enlarged detail of a locking device;

Figs. 9, 10 and 11 are enlarged details of the pivot or trunnion upon which the seat is turned.

Further describing my invention with reference to the drawings, in which like characters of reference denote like parts throughout: 1 and 2 are respectively the rear and front legs of a sofa bed frame, while 4 are the arms and 5 the end panels thereof. A frame work, preferably of metal angles, may be used to connect the rear posts, and consists of the vertical members 5' and the transverse members 6 and 7. Similar strips of metal 8 may be extended across the lower part of the rear leg and form a support and attachment for the panels 5. A seat having the end piece 10, the front or finishing piece 11, and the back piece 12 provided on its normally upper side with upholstery 13 is swung at the ends and overturnable on trunnions 14, which are attached to the end pieces or panels of the frame. The said trunnions are so constructed that the seat and its attachments may be readily removed therefrom, but they are adapted to lock the ends of the frame together by means of the seat and so constructed that accidental removal is practically impossible. The particular mechanism of said pivoting device will be hereinafter more fully described.

A back having side pieces 15, top 16 and upholstery 16' is pivotally connected to the normally rear edge of the seat by means which will also be more fully described later.

A folding bed structure is adapted to be connected to the underside of the seat and extended transversely therefrom in opposite directions. One section thereof having a plurality of end members 17 is attached to the underside of the seat and the ends 17' of said members are extended rearwardly therefrom. To the said extended ends are pivoted at 18 the members 19 which form the ends of the back section. Drop arms 20 are securely attached to the extended portions of the members 17 and are connected near their lower ends by tie pieces 21, to the normally rear portion of the seat, thereby providing means by which at 22 the vertical

framing piece 23 of the back may be attached to the seat. Drop arms 24 are attached to the back-section members 19 at a short distance from the point of their 5 pivotal attachment to the seat member 17. Brackets 25 are secured to the seat section members 17 at points adjacent to their inner ends and have upwardly turned flanges to which at 26 are pivoted end members 27 of 10 the head section. The outer ends of said members are attached to each other by the cross piece 28, and together form a head section for the completed frame. The inner ends 29 of the head section members are 15 formed by cutting away the lateral flange of the angle iron of which the member is composed, thereby leaving the vertical flange which will pass readily by the outer face of the seat member 17 when turned as hereinafter described. Pivots 30 attach the inner ends of said members 29 to one end of connecting bars 31. The other end thereof is pivoted at 32 to the drop arms 24 on the back section members 19.

25 The outer or foot end of the bed frame is formed similarly to the head-section and consists of end members 33 connected by the transverse angle bar 34, thereby forming a foot-section. The inner ends of the end 30 members have the lateral flanges cut away for some distance, leaving the vertical flanges which form levers 36, which are pivoted at 37 to the bracket 38. At the extreme ends said levers are pivoted at 39 35 to one end of connecting bars 40, the other ends of which are pivoted at 41 to the drop arm 20. A pair of legs 42 connected to each other by the cross rod 43 are formed of angle bars, one flange being cut away at the 40 upper end, leaving a flat portion which is pivoted at 37 to the bracket 38. It will be noted that the pivot 37 is the same as that by which the member 33 is secured to the said bracket. Links 45 are pivoted at one 45 end 46 to the upper end of the back framing bars 23 and at the other end 47 to the said legs 42.

An improved foot rest and bedding holder, adapted to be used with the foot section shown, is illustrated in detail in Figs. 6 and 7. The foot section last described is made of angle bars having the transverse flange along the lower edge when extended. The foot board and bedding holder may consist of the vertical members 50 and the transverse member 51, preferably formed in one piece, the extremities of which are turned at right angles to form feet 52. Clips 53 are formed of strips of metal bent midway of 55 their ends to form loops and are pivoted at their ends to the vertical flanges of the head sections by rivets 44. The vertical portions of the bedding holder are received above the upturned portions or feet within the loops of the said clips 53 and are slid-

able therein. When the bedding holder is turned from the position shown in Fig. 6 downwardly to hold the mattress or bedding, the body portions are slid downwardly through the loops in clips 53, thereby taking the position shown in the dotted lines, the extremities of the foot resting upon the horizontal flange of the foot section and securely locking the same in position upon the bedding until the operation is reversed, 75 whereby the foot rest can be turned to its upright position shown. A device by which the initial step of opening and the final step of closing the bed are assisted, and by which the bed is rendered stable and supported in 80 the open position is provided in connection with the head section. A lever 60 is pivoted at one end 61 to the framing strip 8. The other end 62 is attached to one end of a helical spring 63, the other end of which is 85 connected to the outer extremities of the head-section. The free end of lever 60 should swing in contact with a solid support, which may be formed by the framing piece 5, and its forward movement should 90 be limited by a stop 64 or other suitable means.

As the spring 63, in order to overcome the weight of the back and its attachments, must be quite strong, it is important that 95 a secure attachment be provided for the back when in use as a sofa, in order that the same shall not be detached from the frame. For this purpose I use a lock in which a foundation 70 which may be of a short piece of 100 angle iron, is securely attached to a foundation member 16' of the back. On the outwardly projecting flange 71, at 72, is pivoted a latch 73, having the notch 74. The said latch is forced outwardly into engagement 105 with the framing piece 6, by means of a spring 75, and its extension is limited by the bearing of the latch at 76 upon the flange 77. A throw-off piece 78 is pivoted at 79 to the latch. When the back is loosened by the 110 operator, the fingers pressed upon the upper part of said throw-off piece will cause the latch to be disengaged, thereby freeing the back and permitting the movement thereof under the impulse of spring 63. The 115 mechanism described is preferably used in connection with my improved pivot or trunnion by means of which the seat is swung between the end pieces and the frame, and the ends of the seat are locked to the frame, 120 whereby the ends thereof are prevented from spreading. The supporting bracket may be formed by drawing or stamping to provide a flat piece 80, from which projects a boss 81, having the slot 82, provided with lugs 125 83, which are made from the material at the top of the slot and turned backwardly into the cup 84 in rear of the boss 81. A thimble 85 has the neck 86 to be received within the slot 82, which forms a bearing 130

therefor, and shoulders 87 below the neck which bear on the face of the boss adjacent to the slot. A bolt 88, having the head 89 passes through the said thimble and the end 5 10 of the seat frame, and is drawn up by means of a wing nut 90 which holds the several parts firmly in their relative positions.

As represented in Fig. 1 the seat and back of the structure are in their normal relation 10 as when used as a davenport. It will be seen that the seat members 17 and the back members 19 are approximately at right angles to each other. The head members 27 are folded under the seat members and the 15 spring 63 is under tension, the lever 60 being turned forward to its extreme point of movement. The foot-section, together with the supporting legs and the bedding holder, are suspended in a substantially vertical position 20 from the upper part of the back.

When it is desired to use the structure as a bed and to unfold the bed members, the operator takes hold of the central portion of the back piece 16, reaching therebeyond 25 to press the lever 75 of the lock by which the latch 73 is disengaged from the cross piece 6. The tension of the spring 63 starts the seat to turn upon its pivot 14 and advances the back to a point where the overweight 30 of the back and attachments is nearly overcome, whereupon the operator giving a forward pull fully overcomes the overweight, when the apparatus will begin to open out automatically. The pull of opening is communicated 35 by the down arms 24 and the connecting rods 31 to the short arms of members 27 of the head-section. In like manner the pull of opening is communicated from the down arms 20 through the connecting 40 bars 40 to the short arms 36 of the foot members 33. The relative relation of the parts is such that when fully extended the seat and back section members 17 and 19 will be in substantial alinement, while the head and 45 foot sections will be in practical alinement with each other in a plane slightly above that of the back and seat members. The head-section will rest on the spring 63, which is supported by the lever 60, which 50 is now held against further movement by its contact with the framing strip 5. It is at a point slightly before the position shown in Fig. 2 is reached that the overweight is overcome and the automatic forward action 55 of the apparatus begins. It has been a defect in those beds which it has been sought to operate by a straight pull or single movement that the overweight finally becomes too heavy, developing a tendency in the bed to 60 pitch forward upon the operator. This is prevented by the construction shown, in which the link 45 connecting the legs 42 with the foot section 33 passes below the dead center formed at pivot 39 and the legs 65 42 when folded rest upon the foot section.

The principal weight of the legs below the pivot 47, as well as the weight of the back attached to said legs by the links 45 checks the foot section in its tendency to rise under the action of the connecting bars 40. The operator then takes hold of the cross piece 43, thereby revolving the legs 42 on their top pivots 37, and causing the end of the flanges 42' to bear upon the vertical flange of the foot members 35, the weight of the legs and attachments being thereby removed from the foot section and a positive leverage being applied thereto to open the same. The legs are then rotated as shown in Figs. 2 and 5 into their final position, which will be determined by the stops 42". The full extension of the bed structure is completed as the foot section is depressed, whereby the helicals 34', forming a part of the bed fabric and attached to the cross pieces 28 85 and 34 are tensioned and the bed fabric is extended and stretched in position for use. The vertical arms of the bedding holder are drawn through the clips 53 until the feet 52 are in contact with said clip, and the bedding holder is free to be turned to the position shown in Fig. 6.

In reversing the process and closing the bed to restore the structure to its primary use as a sofa, the bedding holder is first turned down and locked upon the bedding. The foot section is raised, thereby releasing the tension on the helicals, and the legs are rotated until they and the foot section together are folded upon the back section 19. 100 The pivotal attachment 39 of the connecting bar 40 is thus placed below the back section, and as the back section is folded upon the seat section the thrust of the connecting bar holds the foot section firmly in relation to the back section. In like manner, as the seat begins to reverse, the head section 27, whose end rests on the spring 63, is rotated so that the pivot 26 passes its dead center and the thrust of the connecting bar 31, 110 given by the drop arm 24, pushes the head section into the position shown in Fig. 2. The further rotation of the seat to its normal position stretches the spring 63, restoring it to the tensioned condition shown in 115 Fig. 1. It will be noted that the tension of the said spring at the latter portion of the movement of the device cushions the same as it assumes its final position, where it is locked by means of the device provided therefor. It will be further noted that the lever 60 in moving forward until its action is stopped, provides an accommodation 120 against too great tension of the spring 63.

Having thus fully described my invention what I claim and desire to secure by Letters Patent is—

1. In a sofa bed having a frame, a seat reversible thereon, a bed section attached to the seat, a back pivotally connected to said 130

seat and having a bed section connected thereto; the combination therewith of a head section having its end members pivotally connected between their ends to the seat section, drop arms on the bed section connected with the back, and bars to connect the said drop arms to the inner ends of the said head section members.

2. In a sofa bed having a frame, a seat reversible thereon, a bed section attached to the seat, a back pivotally connected to said seat and having a bed section attached to the back; the combination therewith of a foot section having its end members pivotally connected between their ends to the back section, drop arms on the seat section, and bars to connect the said drop arms to the inner ends of the said foot section members.

3. In a sofa bed having a frame, a seat reversible thereon, a bed section attached to the seat, a back pivotally connected to said seat and having a bed section attached to the back; the combination therewith of a head section having its end members pivotally connected between their ends to the seat section, drop arms on the back section, bars to connect the said drop arms to the inner ends of the head section members, a foot section having its end members pivotally connected midway of their ends to the back section, drop arms on the seat section, and bars to connect the last mentioned drop arms to the inner ends of the said foot section members.

4. In convertible furniture; two principal bed sections foldable relatively to each other, two auxiliary sections, one being foldable relatively to one principal section and the other being foldable relatively to the other principal section, and means connected to each auxiliary section and operable by the non-adjacent principal section to correspondingly move each auxiliary section relatively to its adjacent principal section.

5. In convertible furniture; a principal bed section, an auxiliary bed section hinged thereto, a second principal bed section hinged to the first, a second auxiliary bed section hinged to the second principal bed section, and means connected to each auxiliary section and operable by the non-adjacent principal section to correspondingly move each auxiliary section relatively to its adjacent principal section.

6. In a sofa bed having a frame, a seat reversible thereon and a bed section on the seat; a head section pivoted to the said seat section, and a spring connected at one end to the free end of the head section and at the other end to the bed frame and adapted to be tensioned when the head section is folded and to act as a support therefor when the said section is extended.

7. In a sofa bed having a frame, a seat reversible thereon and a bed section on the

seat; a head section pivoted to the said seat section, and a spring connected at one end to the free end of the head section and at the other end to the bed frame and adapted to be tensioned when the head section is folded and to act under compression as a support therefor when the head section is extended.

8. In convertible furniture, a bed section adapted to be alternatively folded and extended, a relatively stationary member, a spring attached at one end to said section and at the other end to said member and adapted to be compressed and support the section on said member when extended and to be tensioned when said section is folded.

9. In convertible furniture, a bed section adapted to be alternatively folded and extended, a relatively stationary member, a spring attached at one end to said section and at the other to said member and adapted to be tensioned when the section is folded and to support the same on the said member when it is extended.

10. In convertible furniture, a bed section adapted to be alternatively folded and extended, a relatively stationary member, a spring attached at one end to said section and at the other end to said member and adapted to be compressed and support the section on said member when said section is extended and to be tensioned when said section is folded, said member being movable by the action of said spring to relieve the tension thereof.

11. In convertible furniture, a bed section mounted on a stationary frame work and adapted to be alternatively folded and extended, a lever pivoted to the frame work, and a spring attached to the bed section and to said lever, said lever being adapted to receive and rigidly support the spring when under compression when the bed section is extended and movable to relieve the tension thereof when folded.

12. In convertible furniture, the combination of a frame, a bed section mounted thereon and movable relatively thereto, an auxiliary section pivotally attached to said bed section and alternatively foldable or extendible as the first named section is moved, and a spring having one end attached to the auxiliary section and the other end with relatively less movement connected to the frame, so that said spring will be tensioned when the auxiliary section is folded and will act under compression as a support therefor when the auxiliary section is extended.

13. In convertible furniture, the combination of a frame, a bed section mounted thereon and movable relatively thereto, an auxiliary section pivotally attached to said bed section and alternatively foldable or extendible as the first named section is moved, a lever pivotally supported by the frame,

means for limiting the movement of the lever, and a spring having one end attached to the free end of the lever, so that said spring will be tensioned when the auxiliary 5 section is folded and will act under compression as a support therefor when the auxiliary section is extended.

14. In convertible furniture; an overturnable member, a plurality of principal bed 10 sections pivoted together and connected to said overturnable member, a foot section pivoted to one of the principal sections and foldable thereon, and means connected to and operable by the other principal section to 15 actuate the foot section, said foot section when folded acting under normal conditions to restrain the unfolding of the principal sections relatively to each other.

15. In convertible furniture; an overturnable member, a plurality of principal bed 20 sections pivoted together and connected to said overturnable member, a foot section pivoted to one of the principal sections and foldable thereon, means connected to and operable by the other principal section to 25 actuate the foot section, said foot section when folded acting under normal conditions to restrain the unfolding of the principal sections relatively to each other, 30 and means attached to the foot section and foldable thereon to supplement the restraining action of the foot section.

16. In convertible furniture; an overturnable member, a plurality of principal bed 35 sections pivoted together and connected to said overturnable member, a foot section pivoted to one of the principal sections and foldable thereon, means connected to and operable by the other principal section to 40 actuate the foot section, said foot section when folded acting under normal conditions to restrain the unfolding of the principal sections relatively to each other, and legs 45 connected to the foot section and foldable thereon and adapted in the act of unfolding to engage the foot section and aid in unfolding the same from the adjacent principal section.

17. In convertible furniture; two principal 50 sections pivoted to each other, an auxiliary section pivoted to one of said principal sections, means to connect the auxiliary section and the non-adjacent principal section so as to communicate movement 55 of one to the other, and legs connected to the auxiliary section and foldable thereover to retard the opening movement thereof and adapted in the act of unfolding to engage said auxiliary section and aid in the unfolding thereof.

18. In convertible furniture; two principal 60 bed sections foldable relatively to each other, an auxiliary section attached to one of the principal sections and foldable there-

to, and means connected to the auxiliary section and operable by the non-adjacent principal section to fold the auxiliary section upon its adjacent principal section.

19. In convertible furniture; two principal sections foldable relatively to each other, 70 an auxiliary section attached to one of the principal sections and pivoted so as to be foldable relatively to said attached section, arms extended laterally from the non-adjacent principal section, and rods to connect 75 said arms to the auxiliary section at a point removed from that of its pivotal attachment to its adjacent principal section.

20. In convertible furniture; two principal sections foldable relatively to each other, 80 an auxiliary section having its end members pivotally connected at a point removed from the ends thereof to one of the principal sections, arms extended laterally from the non-adjacent principal section, and rods to connect 85 said arms to the free ends of the end members of said auxiliary section.

21. In convertible furniture; two principal bed sections foldable relatively to each other, an auxiliary section attached to one of 90 the principal sections and foldable relatively thereto, means connected to the auxiliary section and operable by the non-adjacent principal section to move the auxiliary section relatively to its adjacent principal section, and means for elastically holding said auxiliary section when folded relatively to 95 its principal section and rigidly supporting the same when extended.

22. In convertible furniture; two principal bed sections foldable relatively to each other, an auxiliary section attached to one of the principal sections and foldable relatively thereto, means connected to the auxiliary section and operable by the non-adjacent principal section to move the auxiliary section relatively to its adjacent principal section, and a spring device adapted elastically to hold said auxiliary section when 100 folded relatively to its principal section and 105 rigidly support the same when extended.

23. In convertible furniture; two principal bed sections foldable relatively to each other, an auxiliary section attached to one of the principal sections and foldable relatively thereto, means connected to the auxiliary section and operable by the non-adjacent principal section to move the auxiliary section relatively to its adjacent principal section, and a device including a spring and 110 a swinging member actuated by said auxiliary section adapted to elastically hold said section when folded relatively to its principal section and rigidly support the same 115 when extended.

24. In convertible furniture; two principal bed sections foldable relatively to each other both of which are forwardly overturn-

- able and extendible, an auxiliary section pivoted to one of said principal sections and foldable relatively thereto, means attached to said auxiliary section and operable by the principal section non-adjacent thereto to cause the auxiliary section to be folded or extended relatively to its adjacent principal section, and means attached to said adjacent section for retarding the extending movement of said section at a predetermined point. 5
25. In convertible furniture; two principal bed sections foldable relatively to each other both of which are forwardly overturnable and extendible, an auxiliary section pivoted to one of said principal sections and foldable relatively thereto, means attached to said auxiliary section and operable by the principal section non-adjacent thereto to cause the auxiliary section to be folded or extended relatively to its adjacent principal section, spring means for extendibly moving said sections, and means connected with said adjacent section for retarding the extending movement of said sections at a predetermined point. 10
25. In convertible furniture; two principal bed sections foldable relatively to each other and overturnable and extendible, an auxiliary section pivoted to one of said principal sections and foldable relatively thereto, means connected to the auxiliary section and operable by the non-adjacent principal section to fold or unfold the auxiliary section, and supporting legs connected to the auxiliary section and foldable thereover to restrain the unfolding thereof. 15
27. In convertible furniture; two principal bed sections foldable relatively to each other and forwardly overturnable and extendible, an auxiliary head section pivoted to one of said principal sections and foldable relatively thereto, means for holding said auxiliary section elastically in folded relation to said principal section, means attached to the non-adjacent section and connected to the said head section for folding or extending the same, an auxiliary foot section pivoted to the other of said principal sections, means connected to the non-adjacent principal section and attached to said foot section for extending or folding the same, and means connected to said last named principal section for restraining the forward movement thereof. 20
28. In convertible furniture; two principal bed sections foldable relatively to each other and forwardly overturnable and extendible, a head section pivoted to one of said principal sections and foldable relatively thereto, means for holding said head section elastically in folded relation to said principal section, means attached to the non-adjacent principal section and connected to the said head section for folding or extending the same, a foot section pivoted to the other of said principal sections, means connected to the non-adjacent principal section and attached to said foot section for extending or folding the same, and legs connected to the foot section and foldable thereover. 25
29. In convertible furniture having relatively stationary and movable parts, a pivoting device or trunnion therefor comprising a foundation member secured to the said stationary part and a boss hollow on its rear side and provided with a vertical slot having retaining lugs projecting at the upper part of the slot and projecting backwardly therefrom, a thimble having a neck receivable within the said slot to pivot thereon, and a bolt having a head within the recess in the rear of said boss and the body portion passed through said thimble to engage the swinging or movable part. 30
- In witness whereof I have hereunto subscribed my name this 12th day of November, 1915, in the presence of two subscribing witnesses.
